ATTORNEY.

UNITED STATES PATENT OFFICE

HIRAM S. LASHER, OF NEW YORK, N. Y., ASSIGNOR TO UNDERWOOD ELLIOTT FISHER COMPANY, OF NEW YORK, N. Y., A CORPORATION OF DELAWARE

TYPEWRITING MACHINE

Application filed July 17, 1928. Serial No. 293,457.

The present invention relates generally to continuous-billing typewriting machines of the kind disclosed in the patent to Wernery and Smith 1,132,055, and more particularly to means for securing frequent re-registration of superposed forms of a work-web fed through the machine.

Work-webs are often composed of separate web-plies, each ply bearing a succession of forms of the same length. In feeding, outer plies tend to creep ahead of the inner plies, and since this creeping is cumulative it will cause the superposed forms of a set to get out of register if the creeping is not frequently adjusted or corrected. It is usual to bring all the typed forms of a set into re-registration just before the set is severed from the web. Heretofore this re-registering of the forms has usually been secured by providing a plurality of holes through each form-section adjacent the leading edge thereof, and arranging pin-members on the typewriting machine to engage in the holes.

The alignment holes being adjacent the top edge of the form, there is danger of important printed information on the forms being partly obliterated because of cutting the holes. Also, the forms are likely to be torn in handling, and the forms cannot be filed satisfactorily in certain kinds of loose-leaf books. The main object of the invention is to overcome this difficulty.

Heretofore, forms have usually been bound by their top edges, and it has been difficult to lift the sheets sufficiently clear of the binder to gain information as to data and typing which is under or near said binder. An advantage of the invention is that the sheets may be bound by their lower edges, making it very convenient to pick up the top edges and run them over to find any desired sheet.

A feature of the present invention resides in the provision of re-registering pin-members or projections on an Underwood continuous-billing typewriting machine, which are disappearing and normally disposed out of the path of a work-web as its being line-fed thereover in said machine and movable to working positions for engaging in registering holes which are devised adjacent the bottom

edges of sets of forms of the webs. The pins are adjustable crosswise of the web, and may be used with different sizes of forms having varying arrangements of their alignment holes.

In practicing my invention, a paper-table is mounted at the delivery side of the platen for adjustment longitudinally of the web toward and away from the platen. A long slot is provided in the table parallel to the platen and a short distance above the usual cut-off knife, which has a fixed position. Two pin members beneath the paper table are supported by the latter being mounted for lateral adjustment and to be capable of projection upwardly through the slot, to engage in registering holes in the bottom edge portion of each set of forms. Manually-operable means are provided for projecting the pins into the holes in the forms after the carbons are stripped, and while the work-web is still in a straightened condition. The pins may project right up through the printing field of the web, but provision is made for the stripping of the carbons, and for the line-feeding of the web, by dropping the pins out of the path of the carbons and web temporarily.

The re-registering pins are placed right at the delivery side of the platen, immediately in advance of the tear-off knife, where usually a blank space is left upon the form. No holes have to be made at the top of the form, where they would be apt to cut out the printed matter with which the top of a form is usually filled up.

Neither do holes have to be made at the side of the form, which would demand an increase in the width of the web. A device locks the pin-members in effective positions, and the locking device is automatically released upon return of the platen to typing position, and the pin-members are automatically withdrawn from the work-web.

Another feature of the invention resides in the provision of means for making the locking device effective for controlling the pin-members wherever adjusted.

Another feature resides in means for readily providing pin-members of different diam-

eters for fitting snugly in registering holes of different sizes.

Other features and advantages will hereinafter appear.

5 In the accompanying drawings,

Figure 1 is a fragmentary cross-sectional view, front to rear, through an Underwood continuous-billing typewriting machine having my invention applied thereto. The registering pin-members are shown just after being moved to effective positions to engage in holes in a set of forms from which the carbons have been stripped.

15 Figure 2 is a view similar to Figure 1 in which the platen-displacing frame is shown at the moment it is returned from the Figure 1 position to typing position and just before the locking device for the pin-members is released.

20 Figure 3 is a view similar to Figure 2, but at a later stage the platen-frame being shown in typing position and the pin-members having been withdrawn from the holes in the typed form, and the latter partly severed.

25 Figure 4 is a fragmentary front perspective view of an Underwood continuous-billing typewriting machine having my invention applied thereto, the platen-displacing frame being shown in its inverted or displaced position and the pin-members being shown in their normal positions ready to be moved to engage in alignment holes of the leading set of forms from which the carbons have been stripped.

30 Figure 5 is a detail perspective view illustrating the manual projection of the pin-members and the automatic operation of the device which latches the pin-members in projected positions.

35 Figure 6 is a fragmentary front perspective view of the carriage of an Underwood continuous-billing typewriting machine having my invention applied thereto. The platen-displacing frame is shown in position adjacent its normal typing position with the pin-members still in engagement in the alignment holes of a set of forms.

40 In an Underwood continuous-billing typewriting machine of the Wernery-Smith kind, types 10 strike against a platen 11 on a shaft 12 journaled in side plates 13 of a platen-displacing frame 14 which is pivotally mounted on a shaft 15 journaled in the forward ends of a carriage 16. Lower feed-rolls 17 engage against the platen 11, and a rear paper-table 18 guides work-pieces between the platen and the feed-rolls.

45 The platen may be line-spaced by usual instrumentalities, not shown, or by a thumb-wheel 20 fast on the outer end of a stub-shaft 21 which is journaled in the right-hand end plate of the carriage. To the other end of the shaft 21 is fastened a gear-wheel 22 which meshes with a pinion 23 which engages a gear-wheel 24 fast on the platen-shaft 12.

50 A work-web W, having a plurality of separate web-plies 25, may be fed from the rear past the platen, and carbon-sheets 26 may be held interleaved between the plies 25 by a carbon-carrier 27 which runs on a track 28 laterally movable with the carriage, and which has its forward end fastened thereto. The parts mentioned hereinbefore may be of usual construction.

55 Each of the plies 25 of the web W is printed with a succession of forms 30 separated by lines 31. Each form of a web-ply is normally in register longitudinally with a form of each of the other web-plies, such a superposed group of forms being called a set. The carbon-interleaved web-plies 25 are conducted forwardly between two upstanding side-edge gages 32 and pass in a usual way between the displaced platen 11 and a usual cut-off knife 33 mounted on the platen-displacing frame.

60 The creeping of the web-plies 25 is prevented by punching two or more alignment holes 35 through each set of forms adjacent the lower edge thereof, in the typing field of the web, and providing devices which carry pin-members for engagement in the holes when the forms are approximately gaged to cutting-off position by a usual gage 36, which is adjustably mounted on a gage-rod 37, fast to a strong, stiff cross-bar 38, which extends between the side plates 13 of the platen-displacing frame, the cross-bar having transversely disposed T-shaped end portions which are riveted to the side plates.

65 As usually constructed, an Underwood continuous-billing typewriting machine is provided with a paper-table at the delivery side of the platen, which is fixed to the platen-displacing frame. In the device of the present invention, for securing advantages which will presently appear, a paper-table 40 is mounted at the delivery side of the platen for adjustment longitudinally of the web toward and from the platen. Adjustment of the table is secured by providing two elongated slots 41 in the table perpendicular to the bar 38 and fastening the table to the bar by screws 42 whose heads project but slightly above the work-face of the table 40.

70 Pin-members for re-registering the holes 35 may be provided in the form of screws 43, each having a slotted and substantially half-round head 44, an elevation of which is shown in Figure 3. Each screw has a short shank which is threaded in an upward extension 45 of an arm 46 which is disposed substantially parallel to the table 40 a short distance below its normal position. A variety of screws 43, having different sizes of screw-heads 44, may be provided with each machine for use with forms which have different sizes of alignment holes 35, it being understood that the screw-heads should fit snugly in the alignment holes to function properly.

The rear and upper end of each arm 46 is fast to a hub 47 which is slidably mounted on a horizontal rock-shaft 48 journaled in downturned integral ears 49 on the sides of the table 40 adjacent its upper end. The shaft, which is parallel with the platen, may be held against endwise of lateral displacement by a collar 50 which is fastened by a screw 51 and rests against the right-hand ear 49, and by devices at the left-hand end of the shaft, which will be described hereinafter. The shaft 48 has a lengthwise groove 52. Thumb-screws 53 may be tapped in the hubs 47 and have their leading ends turned down to form keys or pin-elements which will fit snugly in the groove 52. These screws are effective to hold the arms 46 securely against lateral movement along the shaft 48 or angular movement therearound, while permitting adjustment of the arms along the shaft.

The pointed heads 44 of the screws 43, which are normally disposed flush with the work-face of the table 40, must at times project up through the table. To permit this movement, and also to permit the screws to be laterally adjustable for use with different widths of forms, which have their alignment-holes 35 spaced at different distances, there is provided a long lateral slot 54, slightly wider than the diameter of the largest screw-heads 44. This slot 54 in the table 40 is parallel to the shaft 48 and platen 11. The slot 54 permits the screw-heads to be projected through the table 40 in any position in which they may be set, in the typing field of the web.

The required data is manifolded on a set of forms 30, and a usual platen-locking lever 55, mounted on a lateral rock-shaft 56, is pushed rearward to released position against the action of a usual spring 58 coiled around the shaft. After swinging the platen-displacing frame to its uppermost position, the carbons 26 may be stripped in the usual way, and the leading ends of the typed set of forms may be pulled up against the cut-off gage 36. In this position of the work-web (Figure 1), the holes 35 of the leading set of forms are positioned substantially opposite the screw-heads 44, and the leading edges of the forms are probably slightly uneven. In this position of the platen-displacing frame 14, it will be noted that the under side of the work-table is turned up and the work-face of the table is turned down.

For moving the screw-heads or re-registering devices 44 through the slot 54, and into the holes 35, the rock-shaft 48 is rocked clockwise against the action of a spring 57 coiled about the rock-shaft. The shaft-rotating means may include a short crank-arm 60 having a hub 61 fastened to the shaft. The arm 60 extends toward the platen and has a flange 62 which serves as a finger-

piece. The spring 57 is formed with a hook 64 to catch upon short arm 63. The other end of the spring is fastened in a hole through a down-turned flange 65 on the upper end of the table 40. A back-stop for the arm 60 is formed by having the toe 63 abut against the flange 65. The spring 57 is effective to normally swing the arms 46 away from the paper-table 40.

The screw-heads or re-registering devices 44 are preferably moved into holes 35 by the operator pressing on the finger-piece 62 with the left hand, this being done just after the right hand (which holds the leading edges of the typed forms against the cut-off gage 36) has started to swing the platen-displacing frame down to normal typing position.

For mechanically holding the re-registering devices 44 engaged in the holes 35 while the platen-frame is being returned the remainder of the way back to typing position, devices are provided which automatically lock the same. The locking devices may include an arm 70 joined to a hub 71, which is fastened by a screw 72 on the left-hand end of the shaft 48, adjacent the left ear 49. It will be noted that the hub 71 co-operates with the collar 50 to prevent lateral displacement of the shaft 48. The arm 70 extends toward the platen 11 alongside a holding piece 73 of a latch generally designated as 74, the piece 73 being pivoted about a screw 75, threaded in an axial hole in one end of a post 76, which has its other end fastened to the cross-bar 38. The outer end portion of the holding piece 73 is disposed below the screw 75 and abuts against the side of the arm 70 adjacent the edge of the latter nearest the table 40 which, in the Figure 1 position, is then the lower edge. A spring 77, coiled about the post 76, has one end fastened to the cross-bar 38 and the other end arranged to urge the holding piece 73 against the arm 70.

When the finger-piece 62 is depressed to the full extent of its throw, the edge of the arm 70, farthest from the table 40, will be moved down enough to let the trigger holding piece 73 snap over it in a counterclockwise direction. A depending stop-flange 78 on the right-hand edge of the holding piece 73 strikes the right-hand side of the arm 70 and arrests the holding piece in effective position over the arm. In this position the arm 70 and the screw-heads 44 are locked against movement away from the paper-table 40. It will be noted that this arrangement for co-operation of the holding piece 73 and the arm 70 permits the latter to be moved toward or from the platen and still coact with the piece.

As the platen-displacing frame 14 is being swung down to typing position, the screw-heads 44, which remain in engagement in the holes 35 in the typed set of forms 30, in effect, clip the web-plies together and prevent displacement of any form relative to another.

The screw-heads are so disposed that the bottom edge of the web-form will be disposed at the cutting edge of the knife when the holes of the form are re-registered by the screw-heads or devices 44.

It is a feature of the present invention to provide simple compact means for unlocking the arm 70, upon return of the platen-displacing frame to typing position, after the 10 web-plies 25 have been gripped between the feed-rolls and the platen 11. To this end, the latch 74 is provided with a trigger-arm 80 joined to the piece 73 at a substantial right angle, and extending leftwardly over the arm 15 70 adjacent the left-hand side plate 13. The inner portion of the trigger-arm 80 is disposed parallel with the cross-bar 38 far enough above arm 70 to permit a counter-clockwise movement of the latter that will 20 be sufficient to withdraw the re-registering devices 44 below the work-face of the paper-table 40. The outer portion of the arm 80 is bent down at an acute angle and is then 25 bent again parallel to its inner portion, so as to be disposed a short distance nearer the paper-table 40 than a usual inreaching locking pin 81 fast in the left-hand side plate 13.

When the platen-displacing frame is swung back to typing position the pin 81 30 strikes a forward cam-edge 82 of a hook 83 on the locking lever 55. A pin 84, fastened to the right-hand side plate 13, engages a cam-edge of a usual locking lever, not shown, which is mounted on the right-hand end of 35 the rock-shaft 56. The pin 81 cams the lever 55 rearwardly until the pin slips under the extreme forward end of the hook 83, whereupon the spring 58 is effective to throw the lever 55 forward, and the hook 83 strikes the 40 trigger-arm 80, which is then disposed just above the pin 81. The platen 11 will have engaged the lower feed-roll 17 just before the hook 83 clears the pin 81. The trigger-arm 80 and the holding piece 73 are swung 45 clockwise enough to cause the latter to be moved clear of the arm 70. The spring 57 is then effective to swing the arm and the arms 46 away from the paper-table 40 and withdraw the re-registering devices 44 from 50 the holes 35. The platen is now locked down by the hook 83 engaging over the pin 81, and the typed set of forms may be severed by the knife 33.

Variations may be resorted to within the 55 scope of the invention, and portions of the improvements may be used without others.

Having thus described my invention, I claim:

1. In a continuous-billing typewriting machine having a platen around which may be fed a work-web including a plurality of separate superposed form-printed web-plies, each form having a plurality of holes adjacent its bottom edge which normally register with the holes of the superposed forms,

the combination with a platen-displacing frame, of a paper-table at the delivery side of said platen mounted on said frame for adjustment toward and from said platen, and provided with a laterally-disposed slot, pin-members supported by said table below the same and disposed opposite said slot, said pin-members being mounted for lateral adjustment, normally inaccessible means for manually moving said pin-members against 70 spring-action through said slot, said means being rendered accessible when said platen-frame is displaced and said work-web is in a straightened condition, to engage the pins in the holes in a typed set of said forms, for 75 bringing the forms into accurate registration with each other, said forms having been slightly displaced by their feeding movement through said machine, devices for locking said pin-members in their effective positions, whereby said pin-members retain said plies while said platen-frame is returned to typing position, and means for automatically releasing said locking devices upon return of said platen-frame to typing position, 80 whereby said pin-members are withdrawn from said forms by spring-action.

2. In a continuous-billing typewriting machine having a platen around which may be fed a work-web having a plurality of separate superposed form-printed web-plies, each form having a plurality of alignment holes adjacent its bottom edge which normally register with the holes of the superposed forms, the combination with a platen-displacing frame, having a web-severing knife and a leading-edge gage, of pin-members mounted on devices supported on said frame arranged for moving said pin-members from normal ineffective positions to engage in said holes, 95 to bring a typed set of forms into accurate registration with each other before they are severed from said work-web, and means for adjusting said pin-members crosswise and lengthwise of said work-web, whereby they 100 may be used with forms of different sizes having varying arrangements of their pin-engaging holes; said pin-members being in proximity to said knife but in advance thereof.

3. In a continuous-billing typewriting machine, having a platen around which may be fed from the rear a composite work-web including a plurality of separate superposed form-bearing plies interleaved with carbons, 110 each form of each ply having a plurality of alignment holes adjacent its bottom edge, the combination with an upwardly-displaceable platen-frame, means for stripping the carbons, and a tearing-off gage against which 115 the leading ends of said web-plies may be abutted when in a straightened condition, of a paper-table at the delivery side of said platen mounted for adjustment lengthwise of said web, web-clipping devices effective for 120

125 130

- preventing longitudinal movement of the separate web-plies relative to each other while said platen is being returned from its displaced carbon-stripping position, said devices including pin-like members supported on said platen-displacing frame below the work-face of said table and mounted for movement in the typing field of the web, to intersect the plane of said table to engage in said alignment holes of said forms, said table having a lateral opening for the passage of said pin-like members therethrough, means for adjusting said pin-like members laterally, and instrumentalities for adjusting said table and said pin-like members together longitudinally of said work-web, whereby said pin-like members may be used with different widths and lengths of forms having different arrangements of alignment holes.
4. The structure described in claim 3, characterized by the pin-like members being supported on the paper-table, and said paper-table being mounted for adjustment longitudinally of the web toward and from the platen on a member of the platen-displacing frame.
5. The device described in claim 2, having means engaging the pin-moving devices for locking said pin-members in their effective web-engaging positions, said means co-operative with the pin-moving devices at all positions to which said pin-members may be so adjusted.
6. In a typewriting machine, having a platen around which may be fed a work-web including separate superposed form-bearing plies interleaved with carbons, each form of each ply having a plurality of alignment holes adjacent its bottom edge, the combination with a displaceable platen-frame, a tearing-off knife, and a tearing-off gage against which the leading ends of said web-plies may be abuted, of a paper-table adjacent to said knife at the delivery side of said platen and mounted for adjustment lengthwise of said web, and pin-like members supported below said table and mounted for upward movement to engage in said holes of said forms, said table having a transverse slot for the passage of said pin-like members, means for adjusting said pin-like members along the slot instrumentalities for adjusting said table and said pin-like members together longitudinally of said work-web, instrumentalities supported by said paper-table for moving the pin-like members through the slot in said table when the platen is displaced, devices supported on said table, other devices co-operating with said table-supported devices for locking said pin-like members in effective engagement in the alignment holes of the work-web, a locking lever for said platen, and an instrumentality mounted for engagement with said lever for automatically releasing the locking devices for the pin-members upon returning the platen-displacing frame to typing position.
8. In a web-manifolding typewriting machine having a platen around which may be fed a composite work-web of loose plies, each web-ply made up of forms, each form having a hole adjacent its bottom edge, the holes in the different plies being in register, said machine also having a platen-displacing frame for straightening out the webs preparatory to stripping the carbons, and also having a web-severing knife, and a gage for the leading end of the web, the combination of a paper-table mounted on said displaceable frame at the delivery side of the platen, a web-reregistering pin, means for holding said pin upon said table for projection into the holes in the webs to reregister the same, said pin being in advance of the knife but in proximity thereto to engage said hole in the lower end of the form, means operable upon said pin, after the web has been straightened out and the carbons have been stripped, for projecting the pin through the holes in the web-plies to reregister the same, preparatory to tearing off the typed form, whereby the typed form may be torn off by said knife with the succeeding form in reregistered condition, and means for retracting said pin, said pin being adjustable towards and from said knife, and said leading-edge gage being independently adjustable towards and from said knife.
9. In a web-manifolding typewriting machine having a platen around which may be fed a work-web

- fed a composite work-web of loose plies, each web-ply made up of forms, each form having a hole adjacent its bottom edge, the holes in the different plies being in register, said machine also having a platen-displacing frame for straightening out the webs preparatory to stripping the carbons, and also having a web-severing knife, and a gage for the leading end of the web, the combination of a paper-table mounted on said displaceable frame at the delivery side of the platen, a web-reregistering pin, means for holding said pin upon said table for projection into the holes in the webs to reregister the same, said pin being in advance of the knife but in proximity thereto to engage said hole in the lower end of the form, means operable upon said pin, after the web has been straightened out and the carbons have been stripped, for projecting the pin through the holes in the web-plies to reregister the same, preparatory to tearing off the typed form, whereby the typed form may be torn off by said knife with the succeeding form in reregistered condition, means for retracting said pin, and a side gage for the web, said pin being mounted for adjustment longitudinally of said platen upon said table, and said table being mounted for adjustment towards and from said knife, together with said pin.
10. In a web-manifolding typewriting machine having a platen around which may be fed a composite work-web of loose plies, each web-ply made up of forms, each form having a hole adjacent its bottom edge, the holes in the different plies being in register, said machine also having a platen-displacing frame for straightening out the webs preparatory to stripping the carbons, and also having a web-severing knife, and a gage for the leading end of the web, the combination of a paper-table mounted on said displaceable frame at the delivery side of the platen, a web-reregistering pin, means for holding said pin upon said table for projection into the holes in the webs to reregister the same, said pin being in advance of the knife but in proximity thereto to engage said hole in the lower end of the form, means operable upon said pin, after the web has been straightened out and the carbons have been stripped, for projecting the pin through the holes in the web-plies to reregister the same, means for locking said pin in its projected position to enable it to hold the plies together while the displaced platen-frame is being returned, and means for automatically withdrawing said lock upon the return of the platen-frame, said pin being adjustable relatively to the web, and the locking and withdrawing means being effective at all adjustments of the pin.
11. In a web-manifolding typewriting machine having a platen around which may be fed a composite work-web formed of loose plies, each web-ply made up of forms, each form having separated holes adjacent its bottom edge, the holes in the different plies being in register, said machine also having a platen-displacing frame for straightening out the webs preparatory to stripping the carbons, and also having a web-severing knife, and a leading-edge gage, the combination of a paper-table mounted on said displaceable frame at the delivery side of the platen for adjustment, reregistering pins, means for holding said pins upon said table for projection into the holes in the webs to reregister the same, said pins being in advance of the knife and in proximity thereto to engage the holes in the lower end of the form, means for projecting said pins through the holes in the web-plies to reregister the same, means for retracting said pins, said pins being adjustable independently of each other longitudinally of the platen, and means for effecting adjustment of the pins as a unit towards and away from said knife, at all adjustments of the pins along the platen.

HIRAM S. LASHER.
